BALING PRESS

Alford C. Barrows, Harold L. Haines, and George W. Langford, Ann Arbor, Mich., assignors to Economy Baler Company, Ann Arbor, Mich., a corporation of Michigan

Application June 28, 1937, Serial No. 150,842

8 Claims. (Cl. 100—19)

The invention relates to baling presses and more particularly to that type in which the material to be compressed is first introduced into a well arranged beneath the compression chamber and from which it is lifted and compressed by a vertically moving platen. With such constructions it is usual to arrange the compression chamber above the floor and to provide hinged sides which after compression may be swung outward to permit of removal of the bale. The well for receiving the material to be compressed extends beneath the floor and should be of considerable length to hold a sufficient amount of loose material to form a full bale. However, there are practical limits to the space available for this purpose and furthermore an excessively deep well will proportionately increase the cost of the apparatus.

It is one of the objects of the present invention to obtain a construction in which the well may be filled a plurality of times to form a single bale. This reduces the depth required but necessitates provision for holding the compressed portions of the bale during the refilling operation, and also means permitting of such refilling. Other objects of the invention are to facilitate opening of the compression chamber and the removal of the compressed bale therefrom and further to provide for encasing the bale with an outside wrapping, and in general to simplify and improve the structure. With these objects in view the invention consists in the construction as hereinafter set forth.

In the drawings:

Figure 1 is a perspective view of the baling press showing the feeding door in open position;

Figure 2 is a front elevation of the compression chamber with the doors closed;

Figure 3 is an elevation of the movable platen showing the false platen in engagement therewith;

Figure 4 is a horizontal section on line 4—4 of Figure 2;

Figure 5 is a sectional end elevation of the fixed end of the compression chamber;

Figure 6 is a similar view of the opposite end showing the locking mechanism for the hinged sections;

Figure 7 is an end elevation of the movable platen and false platen;

Figure 8 is a plan view of the locking mechanism for the small door.

In general construction the press comprises a frame A which extends the full length to include the compression chamber and the well beneath the same. This frame is formed of suitable vertical and horizontal structural elements which together form a rectangular structure. The portion of the frame which extends above the floor is open at front and rear so as to permit of the

outward swinging of the hinged members forming the compression chamber. The well B which extends beneath the floor is formed of front, rear and end plates which are connected to and reinforced by the frame A. C is a stationary platen which is mounted at the top of the frame A, and D is the movable platen normally at the lower end of the frame. This platen comprises a beam D' which extends centrally through the well B and is movable upward through slots B' in the end walls. The platen is raised by a suitable power actuated lifting mechanism, the detailed construction of which forms no part of the present invention and which, therefore, is not illustrated.

The compression chamber which extends above the floor comprises an end wall E, front and rear walls F hinged to the wall E and opposite end wall sections G carried by the walls F. These together form a rectangular compression chamber which is in alignment with and of the same dimensions as the well B and which has central slots in the end walls in alignment with the slots B' for the upward passage of the beam D'.

As usually constructed, the hinged sections of the compression chamber extend the entire height thereof and when opened will uncover a full bale. These sections are also opened for the introduction of the material into the well which after closure of the sections and the upward movement of the platen, is compressed into the chamber to form the bale. With such construction, after the hinged sections are once closed they cannot be opened until the bale is to be removed, and therefore if the material originally pressed in the well is insufficient to form a full compressed bale there would be no means of adding to it. This difficulty is overcome by forming the hinged members in upper and lower sections F', F'' and with the lower sections capable of being independently opened while the upper sections remain in closed and locked position.

Thus assuming that the original filling of the well when compressed will only occupy the space enclosed by the upper sections, then by retracting the platen and opening the lower sections the well may be refilled and this material compressed to be added to the previous charge for forming the full bale. It is apparent that if the platen is lowered after the compression of the first charge, some means must be provided for retaining the compressed charge, as otherwise it would expand by its inherent resiliency and drop with the platen into the well. Such retaining means is formed by a series of dogs H which are hinged to the front and rear upper door members F' and extend inward through slots H' into the path of the platen and material being compressed thereby. During such compression the dogs will be displaced by the rising material and

5 moved outward through the slots H' until the platen has moved upward above the same. The dogs will then fall backward beneath the platen which latter has registering slots H' permitting it 10 to pass the dogs during its downward movement while the compressed charge will be retained thereby. As specifically shown, the dogs H are mounted upon a shaft H² which is journaled in brackets H³ mounted on one of the reinforcing 15 bars F². Thus, it will be understood that after the platen D has been returned to the bottom of the well, the lower door sections F² may be opened permitting of the refilling of the well, while the previously compressed charge is retained by the dogs H. The door sections F² are then again closed and the platen is raised to compress another charge which will be added to that previously compressed.

20 During the final compression of the bale the walls of the compression chamber will be subjected to very high pressures tending to distort the same. Any such distortion of the permanent end wall E may throw the axes of the hinges for the upper and lower door sections out of 25 exact alignment so as to interfere with accurate closing. To guard against such result the end wall E is reinforced from the main frame A through the medium of brace members. These include horizontal members A² on the main 30 frame which are connected by transversely extending bars I with reinforcing bars E² on the end panel E on opposite sides of the slot therein. The outer ends of these bars E² form the hinge brackets to which the members F are pivotally 35 secured and to hold these in proper alignment, turnbuckles J are arranged between the bars A² and said members E². There are preferably two of these turnbuckles J for each of the lower and upper hinged sections F', F², thereby permitting 40 of adjustment which will properly align the axes of the hinges.

45 The members F' and F² are reinforced by spaced bars F³ shown as I-bars, the webs of which are extended to form hinge members for cooperating with those on the bars E², such cooperating members being connected by the pivots F⁴. The end sections G are secured to the reinforcing bars F² by angle bars G' so as to be held in rigid relation to the sections F'. There are 50 also reinforcing angle bars G² adjacent to the inner edges of the sections G and the slots between the same. These hinged sections are held in closed position by a locking mechanism of the following construction:

55 K are hooked locking bars pivotally attached at K' to the angle bars G' and arranged respectively near the upper and lower ends thereof. The hooks or angle flanges of the members K are adapted to engage with keepers preferably 60 formed by rollers L mounted upon an angle bar L' which in turn is supported by vertically extending bars L² attached to the main frame. To engage the members K with their keepers they are actuated by links M connected to a 65 crank M'. This crank may be rotated by suitable mechanism which as shown comprises a gear segment M² thereon which is in mesh with a worm M³ actuated by a shaft M⁴ having a hand wheel M⁵. The arrangement is such that 70 after the bale is compressed the operation of the handle M⁵ through the intermediate mechanism will move the members K gradually out of engagement with the roller keepers L thereby avoiding any sudden release of the pressure. As the 75 operating mechanism is irreversible the lock can-

not be accidentally released by the expansive pressure of the bale. Also, this mechanism provides high leverage for completely closing the hinged sections. The members G, together with the reinforcing angle bars G' therefor, extend 5 downward below the door F' and form a seat against which the door F² closes. The door F² is normally locked in closed position by bolts N engaging keepers N' on the bar G'. The bolts are retracted by rock arms N² on a rockshaft N³ which 10 is actuated by a lever N⁴. Thus, normally the door F² will open or close with the door F', but it may at any time be independently opened by withdrawing the bolts N.

15 It is sometimes desirable to enclose the bale in a fabric wrapper, such as burlap. To facilitate this the platen D may be provided with a false platen D² which rests thereon and which comes into direct contact with the material to be compressed. This false platen comprises longitudinally extending structural bars D³ and transversely extending plates D⁴ which are slightly spaced from each other to provide grooves for the insertion of the binding wires. The bars D³ are spaced slightly inward from the outer ends 25 of the plates D⁴ so as to leave beneath the latter a space in which a roll of burlap may be stored, and the opposite ends of the bars D³ are also beveled to leave space for receiving the wrapper. With such construction, burlap strips are extended across the top of the false platen and with end portions rolled and stored in the marginal spaces beneath the plates D⁴. After the bale is compressed and tied the rolled extensions 30 of the burlap strips may be drawn upward over the bale and sewed together to form a complete 35 wrapper.

With the press constructed as above described, in use, the material to be compressed is first introduced into the well either by opening both 40 upper and lower doors F', F² or only the lower door F². When the well is full the doors are closed and locked and the material is compressed by the upward movement of the platen D, actuated by suitable mechanism not described. If 45 the quantity of loose material in the well is insufficient to form a full compressed bale, it will be carried upward into the space closed by the upper door F', the dogs H being first forced outward and subsequently dropping inward after the 50 passage of the platen, as previously described. The platen is then lowered and the lower doors F² are opened for the introduction of more of the loose material into the well. This is compressed by the succeeding upward movement of 55 the platen, and these operations may be repeated as often as necessary to form a full bale.

Compressed bales have a certain degree of resiliency causing them to expand when the compression pressure is first released. Thus if the 60 doors of the compression chamber were suddenly unlocked the expansion of the bale might swing these open with violence. Such effect is avoided by our locking mechanism in which the locking hooks are gradually disengaged from the roller keepers and are sufficiently cammed so as to permit a certain degree of opening of the doors before complete release of the same. This takes 65 up the expansion of the bale, after which the doors may be opened without danger. Also, the fact that an irreversible mechanism is used between the hand-operated wheel M⁵ and the locking hooks, prevents any tendency to unlock by the expansive pressure of the bale.

What we claim as our invention is:

1. In a baling press, the combination with a well for receiving material to be compressed, a platen movable upward in said well, and a compression chamber into which the material in said well is compressed being of a capacity substantially corresponding to that required for forming the normal size of compressed bales and having laterally relatively movable sides adapted to be opened for the removal of the bale therefrom, of means for retaining compressed material in a portion of said compression chamber permitting the return of said platen, and means for opening another portion of said compression chamber beneath the compressed material for introducing additional material therein and into said well whereby a succeeding upward movement of said platen will compress this material and add the same to the material previously compressed in a portion of the compression chamber, said last mentioned means being in one of said relatively movable sides.

2. In a baling press, the combination with a well for receiving the material to be compressed, a platen movable upward in said well, and a compression chamber into which the material in said well is compressed being of a capacity substantially corresponding to that required for forming the normal size of compressed bales and having laterally relatively movable sides adapted to be opened for the removal of the bale therefrom, of dogs for retaining compressed material in a portion of said compression chamber insertable therein beneath said platen, the latter being slotted to permit of return movement past said dogs, a door in a portion of said compression chamber beneath said dogs adapted to permit of the introduction of additional material into the well and the compression of the same on the subsequent upward movement of the platen to be added to the material previously compressed in a portion of the compression chamber, said door being in one of said relatively movable sides.

3. In a baling press, the combination with a well for receiving the material to be compressed, a platen movable upward in said well, and a compression chamber into which the material in said well is compressed being of a capacity substantially corresponding to that required for forming the normal size of compressed bales and having laterally relatively movable sides adapted to be opened for the removal of the bale therefrom, of dogs hinged outside said compression chamber in registration with slots in a wall thereof and in said platen being adapted to be swung inward beneath the platen to retain the compressed material when the platen is returned, and a door in said compression chamber beneath said dogs for introducing additional material into the well to be compressed by a subsequent upward movement of the platen and added to the previously compressed material in a portion of the compression chamber for forming the bale, said door being in one of said relatively movable sides.

4. In a baling press, the combination with a well for receiving the material to be compressed, a platen movable upward in said well, and a compression chamber into which the material in said well is compressed being of a capacity substantially corresponding to that required for forming the normal size of compressed bales and having

laterally relatively movable sides adapted to be opened for the removal of the bale therefrom, of an auxiliary door in a portion of one of said relatively movable sides of said compression chamber, and means for retaining compressed material in said compression chamber above said auxiliary door permitting the return of said platen whereby additional material may be introduced through said auxiliary door and compressed by a subsequent upward movement of the platen. 10

5. In a baling press, the combination with a well for receiving the material to be compressed, and a platen movable upward in said well, of a compression chamber above said well into which the material is compressed by said platen, said chamber being of a capacity substantially corresponding to that required for forming the normal size of compressed bales and having a hinged side adapted to be opened for the removal of said bale, means mounted on said hinged side insertable into said compression chamber to retain compressed material in a portion thereof when said platen is returned, and an auxiliary door in said hinged side beneath said retaining means permitting the introduction of additional material into said well in sufficient amount when compressed to complete the filling of said compression chamber and to form with that previously compressed a full size bale. 20

6. In a baling press, a compression chamber 30 provided with a stationary side, a side portion hinged to said stationary side extending for a part of the height thereof, a complementary side portion also hinged to said stationary side, a reinforcing frame, and a plurality of braces 35 extending from said frame to the hinged edge of said stationary side, said braces being individually adjustable to align the hinge axes of the complementary sections with each other.

7. In a baling press, a compression chamber 40 provided with a stationary side, transversely extending reinforcing members for said side, complementary side portions adjacent to said stationary side each provided with transversely extending reinforcing members, the reinforcing 45 members of said stationary and complementary sides being extended and pivotally connected to form hinges, a reinforcing frame and a plurality of braces extending from said reinforcing frame to the reinforcing members of said stationary 50 side adjacent to the hinged end thereof, said braces being individually adjustable for the alignment of the hinges with each other.

8. In a baling press, a compression chamber provided with a stationary side, transversely extending reinforcing members for said side, complementary side portions adjacent to said stationary side each provided with transversely extending reinforcing members, the reinforcing 55 members of said stationary and complementary 60 sides being extended and pivotally connected to form hinges, a reinforcing frame and a plurality of turnbuckle braces extending from said reinforcing frame to the reinforcing members of said stationary side adjacent to the hinged end thereof, whereby said turnbuckles may be individually adjusted to align the axes of said hinges with each other. 65
